UNITED STATES PATENT OFFICE.

JOHN R. WILLIAMS, OF SCRANTON, PENNSYLVANIA.

DESIGN FOR A HORSESHOE-CALK.

SPECIFICATION forming part of Design No. 26,156, dated October 6, 1896.

Application filed July 31, 1896. Serial No. 601,251. Term of patent 7 years.

To all whom it may concern:

Be it known that I, JOHN R. WILLIAMS, a citizen of the United States, residing at Scranton, in the county of Lackawanna and 5 State of Pennsylvania, have invented and produced a new and original Design for Horseshoe-Calks; and I do declare the following to be a full, clear, and exact description of the same, reference being had to the accompanying drawings, forming a part hereof.

Figure 1 is a top view of a horseshoe-calk, showing my design when held in the position shown in Fig. 2. Fig. 2 is a side elevation of the same. Fig. 3 shows a cross-section of the 15 same on the line $x-x$ of Fig. 2, these three views being deemed necessary to fully illustrate my design.

The leading feature of my design consists in a cubical portion A, having triangular py-

ramidal portions $a-a-a-a$ removed from its 20 four lateral surfaces, after its top side c has been slightly rounded, so as to represent, before the aforesaid portions are cut away, a portion 25 of the surface of a true sphere, the same having a cylindrical screw-threaded portion B, with its axis in line with the vertical axis of the cubical part A extended from the middle of the lower surface b of the cubical part.

What I claim is—

The design for a horseshoe-calk substantially, as herewith shown and described.

In testimony whereof I affix my signature in presence of two witnesses.

JOHN R. WILLIAMS.

Witnesses:

GEORGE W. DUNN,
JOHN LUXEMBURGER.
